[57] CLAIM

The ornamental design for a ring towel holder, as shown and described.

DESCRIPTION

FIG. 1 is a front perspective view of a ring towel holder showing my new design;

FIG. 2 is a reduced scale rear elevational view thereof;

FIG. 3 is an enlarged top plan view thereof;

FIG. 4 is an enlarged bottom plan view thereof; and

FIG. 5 is an enlarged right side elevational view thereof, the left side being a mirror image and being shown broken away for ease of illustration.

FIG. 1

FIG. 2

FIG. 3

FIG. 4

FIG. 5
